(57) **CLAIM**

The ornamental design for a compact digital camera body, as shown and described.

DESCRIPTION

FIG. 1 is a top, left, and front perspective view of a compact camera body, wherein the broken lines show environment that may accompany the camera body and form no part of the claimed design;

FIG. 2 is a top, right, and front perspective view thereof;

FIG. 3 is a top, left, and rear perspective view thereof;

FIG. 4 is a top, right, and rear perspective view thereof;

FIG. 5 is a bottom, right, and front perspective view thereof;

FIG. 6 is a front end view thereof; and,

FIG. 7 is a rear end view thereof.
